UNITED STATES PATENT OFFICE.

STANISLAW NOWOSIELSKY, OF NEW YORK, N. Y.

LOCK.

1,206,724.

Specification of Letters Patent. Patented Nov. 28, 1916.

Application filed December 31, 1914. Serial No. 379,836.

To all whom it may concern:

Be it known that I, STANISLAW Nowosiel-sky, a subject of the Czar of Russia, residing at New York, borough of Manhattan, in the county and State of New York, have invented new and useful Improvements in Locks, of which the following is a specification.

My invention relates to locks for general use, and specifically to locks operated by keys and yet possessing some of the attributes of combination locks; that is to say the combination is made in two parts mating each other, one of said parts being housed within the lock casing and the other carried by and incorporated within the structure of the key, so that a particular lock can not be operated except by a particular key.

Among objects sought to be accomplished by my invention are the following:—I. To fit the two mating parts of the combination to each other by first shaping the part carried by the key so as to give the same a predetermined arbitrary form, and then shaping the part housed within the lock casing so as to bring it into conformity with the key. II. To increase the difficulty of operating the lock without exact knowledge of the combination, and to increase the difficulty of ascertaining the combination, by giving an asymmetrical form to the active parts of the combination used for controlling movements of the bolt. III. To increase the range of combinations possible, other things being equal, so that a lock of small size may have its combination changed a considerable number of times, or a large number of such locks, alike except as to the combinations employed, may be each responsive to its individual key and to no other key. IV. To simplify the lock mechanism and give the same, suitable form for use in a vast multitude of locks, used for widely divergent purposes. V. To improve the general efficiency of the lock, and to cheapen the cost of its manufacture.

Reference is made to the accompanying drawings forming a part of this specification, and in which like letters indicate like parts.

Figure 1 is a vertical section on the line 1—1 of Fig. 2, looking in the direction of the arrows, and showing one form of the lock casing and some of the mechanism therein. Fig. 2 is a vertical section taken approximately on the line 2—2 of Fig. 1,

looking in the direction of the arrows. Fig. 3 is a fragmentary elevation showing the inner face of a door to which the lock is applied. Fig. 4 is a side elevation of the same, disclosing one edge of the door. Fig. 5 is a fragmentary section of the line 5—5 of Fig. 2 looking in the direction of the arrows but showing the key inserted within the lock. Fig. 6 is a fragmentary elevation of the key, showing a pair of ward sectors detachably secured thereto and each serving as an actuating part of the lock combination. Fig. 7 is an inverted plan of the mechanism shown in Fig. 6. Fig. 8 is a detail, showing one of the dolly pins and its immediate surroundings. Fig. 9 is a front elevation of a sector located within the lock casing and carrying teeth which are staggered to form a labyrinth, the latter being part of the lock combination. Fig. 10 is an inverted plan of the labyrinth sector shown in Fig. 9. Fig. 10^a is a fragmentary elevation of the rocking barrel of the lock, carrying loose dolly pins provided with portions co-acting with the ward sectors, and with other portions co-acting with the labyrinth, all for the purpose of enabling the ward sectors of the key to control rocking movements of the rocking shaft of the lock. Fig. 11 is an inverted plan showing a form of labyrinth sector differing slightly from the one shown in Figs. 9 and 10. Fig. 11^a is a view somewhat similar to Fig. 10^a, but showing the dolly pins and parts carried thereby as arranged for use with the labyrinth sector shown in Fig. 11. Fig. 12 is a perspective showing my improved lock adapted for use as a padlock. Fig. 13 is a section through the padlock, taken on the line 13—13 of Fig. 15, looking in the direction of the arrows. Fig. 14 is a section through the padlock, taken on the line 14—14 of Fig. 15, looking in the direction of the arrows and showing the key inserted. Fig. 15 is a section through the padlock, taken on the line 15—15 of Fig. 13, looking in the direction of the arrows. Fig. 16 is a fragmentary perspective of a sliding bolt and hasp used on parts of the padlock.

A door is shown at 17 and a jamb at 18, the latter being provided with a face plate 20 and also with a passage 21 extending through this face plate and adapted for registry with the bolt pocket 19. The lock casing appears at 22, and may have a

- desired form. In this instance it has the form of a short cylinder provided with a head 23, the latter being sunken flush with the inner face of the door, as indicated in Fig. 2. The casing is further provided with a head 24 which has a thickened portion 24^a integral with it and serving to support the key when the latter is inserted into the casing, as hereinafter described.
- 10 The casing is provided with a web 25 extending across it after the manner of a chord, and integral with this web is a massive portion 25^a serving as a shoulder. A sliding bolt 26 rests upon the web 25 and is stopped in one direction of its thrust by lodging against the shoulder 25^a. When the bolt is moved away from the shoulder 25^a it extends into the bolt pocket 19 and thus locks the door.
- 15 For the purpose of actuating the bolt I provide it with rack teeth 27. Meshing with these rack teeth are gear teeth 28 which are integral with a barrel 29, the latter having the general form of a sector. The barrel 29 is provided with a collar portion 30, and carries a set screw 31 extending through this collar portion. The barrel also carries a disk 29^a, integral with it and therefore movable, but serving essentially as a guard or partition for protecting most of the movable parts of the lock. A spindle 32 extends through the heads 23 and 24, and is coaxial with the casing. Knobs 33 and 34 are mounted rigidly upon the ends of the shaft 32, and used for turning the same by hand so as to move the bolt 26 back and forth in the general direction of its length; that is, whenever the barrel 29 is free to rock, as hereinafter described.
- 20 Carried by the barrel 29 and extending loosely through the same in a direction parallel with the shaft 32, are a number of dolly pins 35, 36, in this instance two in number, so arranged that when the shaft 32 is rocked the dolly pins move bodily in arcs which are concentric—that is they may be considered as struck from the axial line of the shaft as a center. The dolly pins 35, 36 are engaged by leaf springs 37, 38, which are secured upon the barrel by fastenings 39, 40. The barrel 29 is provided with slots 41, 42 (see Fig. 10^a) one adjacent each dolly pin, and extending through each slot are guide pins 43, 44, there being one pair of guide pins integral with or rigidly affixed to each dolly pin. The dolly pins are provided with suitably shaped ends, 35^a, 36^a, for engaging the ward sectors of the key.
- 25 The casing 22 is provided with a pair of guide plates 45 which have edges 46 formed into slideways. Engaging these slideways is a member 47 having the general form of a sector, and which, because of its function, I designate as a labyrinth sector. It is provided with a lug 48 integral with it, and ex-
- tending through this lug is a crank 49 carried by a revoluble shaft 50, the latter being journaled in bearings 50^a and provided with a small knob 51 whereby it may be rocked or turned, so as to raise and lower the labyrinth sector. The labyrinth sector is provided with a number of teeth 52, 53, which are staggered as indicated in Fig. 10, and arranged in rows corresponding in number to the number of dolly pins. The teeth may, if desired, have the form indicated at the time the labyrinth sector is cast or otherwise manufactured, but preferably the teeth are first made of larger size and uniform symmetrical shape and afterward filed or trimmed into arbitrary forms as shown in Fig. 10. In all cases the forms given the teeth must be related to the forms given the ward sectors of the key, and reckoned from the latter as a basis. In other words, the form of the ward sectors of the key is first determined and the teeth of the labyrinth sector are shaped accordingly.
- 30 In some instances, as shown in Fig. 11, I provide the labyrinth sector 54 with teeth of the form shown at 55, 56, arranged in double rows, each having a crooked or asymmetrical path 57 between its teeth and extending throughout the row. Where this form of labyrinth sector is used I employ a barrel of the form shown at 58, from which guide pins 59, 60, adapted to pass between the teeth 55 or 56 of each double row, or in other words to follow the paths 57, provided the guide pins 59, 60 which are carried by the dolly pins, are moved therewith relatively to the barrel 58 as the latter is rocked. Similarly if the labyrinth sector 47 shown in Fig. 10, be used in connection with the barrel 29 shown in Fig. 10^a, the row of teeth 52 is straddled by the guide pins 43 and the row of teeth 53 is straddled by the guide pins 44. Thus the barrel 29 can now be rocked regardless of the teeth 52, 53 provided the guide pins 43, 44, under control of the dolly pins carrying them, be moved properly in relation to the barrel 29 so as to remain astride the rows of teeth 52, 53 as the barrel is rocked.
- 35 The casing 22 is provided with a key hole 61, having any suitable shape. In this particular instance it is merely a narrow slot of arcuate form, and at the ends of this slot are stationary guides 62. The key is shown at 63, (see Fig. 6) and is provided with edges 64 for engaging these guides 62. The key is also provided with an arcuate surface 65 and with a hole 66, into which fits a screw 67. The ward sectors are provided with serrated asymmetrical surfaces 70, 71, which are formed by cutting, stamping, or filing as desired. Each ward sector thus presents a surface the contour of which can not easily be guessed, and can not be determined by calculation or by any method

heretofore employed for ascertaining the secret of a combination. Moreover the operating surfaces of the respective ward plates are individually distinct, so that 5 knowledge of the shape of one of them is not effectual for obtaining knowledge of the form of the other. The ward sectors together constitute a part of the combination for controlling the lock, and the number of 10 permutations possible is limited only by the number of changes which may be made in each and all of the ward sectors. Moreover as each ward plate is shorter than the arcuate surface 65 of the key, the ward sectors 15 may be overlapped to any desired extent, dependent upon the will of the operator, before the ward sectors are secured by the screw 67; that is, before the ward sectors are drilled to accommodate the 20 screw. Thus by shifting the relative positions in which the ward sectors may be secured to the key, the number of permutations possible may be still further increased.

The key 63 is provided with a shoulder 25 integral with it, and when the key is inserted through the keyhole 61, as indicated in Fig. 15, the shoulder 72 engages the adjacent inner surface of the casing, at the adjacent edge of the keyhole, and thus holds 30 the key in position, the screw 67 resting upon the annular thickened portion of the casing 24^a.

The action of the mechanism thus far discussed is as follows: The parts being assembled and arranged as described, a key is inserted through the keyhole 63. If the key is not the proper one for this individual lock, or in other words if the teeth of the labyrinth sector 47 or 54 of the lock have 35 not been specially staggered and otherwise arranged according to the contour of the operating surfaces 70, 71, of the ward sectors carried by the key, any attempt to rock the shaft 32 must be ineffectual. If any 40 effort be made to turn either knob 33 or 34, some one of the teeth of the labyrinth sector must be directly in the path of travel of one of the guide pins carried by the drum. As the drum can not be rocked, the lock 45 cannot be actuated. Suppose, however, that the key 63 is the proper one to control the lock, and that one of the knobs 33, 34 is turned. The rocking of the barrel is now unimpeded. The dolly pins, being spring- 50 pressed against the ward plates 68, 69 and also partaking of the general rocking movement of the barrel travel in zigzag or asymmetrical paths, dependent upon the forms 55 and relative positions of the ward sectors of the key. Hence, the guide pins carried by the dolly pins dodge the teeth of the labyrinth sectors and the shaft 32 is now free to turn or rock. The bolt 26 is thus 60 readily slid endwise or shot by merely turning. To throw the lock out of action,

the knob 51 is turned by a person within the room controlled by the lock. The labyrinth sector is thus raised so that its teeth are unable to interfere with free movement of the guide pins, and the drum is thus left 70 free to rock.

In some instances I use my invention in the form of a padlock, as indicated in Figs. 12, 13, 14 and 15. The casing is shown at 75 73 and in this instance is cylindrical as in the door lock. No knob 51 is used, and if the casing employed be one otherwise suitable for a door lock, the knob 51 is simply removed, as indicated in Fig. 15. It is possible however in this form to have the labyrinth sector integral with the casing, or at least secured rigidly to the latter. The bolt is provided with a tongue 77. A hasp or latch 78 is mounted upon a cross pin 79 and is provided with an end portion 80 85 for engaging the tongue 77. The casing is provided with an opening 81 to admit the end portion 80. A disk 29^a, carried by the barrel, serves as a guard for the lock mechanism generally. The hasp or latch 78 is 90 held or not by the bolt 74 according to the position into which the bolt is thrust, and movements of the bolt are controllable by rocking movements of the shaft 32.

Except as otherwise designated above, the 95 structure and action of the form shown in Figs. 12 to 16 inclusive is the same as for the other forms of the lock.

From the foregoing description it will be noted that my device as a whole is provided 100 with combination mechanism, and that the combination is in two parts—a driven or passive part and an actuating or controlling part; and that the driven or passive part is housed within the lock casing, while the 105 actuating or controlling part, is carried by the key.

I will now describe how the two general parts of the combination are made and brought into conformity with each other. 110 First, the ward sectors 68 and 69 are cut or stamped out of suitable material, say thick sheet metal, each of the ward sectors receiving the distinctively delineated surface 70 or 71, which is purposely made 115 asymmetrical—that is, its operating surface is preferably haphazard or zigzag. Next the ward sectors are curved, one is brought to overtop the other to any desired extent, and the sectors are next secured to, and 120 made virtually a part of, the key. This done the key is used as a master member or pattern, for working out the part of the combination housed within the lock casing; in other words for controlling the delineation to be given to the rows of teeth carried by the labyrinth sector. A convenient way to bring the labyrinth sector 125 into conformity with the shape of the ward plates is to first make the labyrinth sector 130

with its teeth rather large, and distributed uniformly; then cause the guide pins 43, 44, (or 59, 60) to mark the teeth, so as to indicate how they should be cut or otherwise shaped; and finally to execute the alterations thus indicated. In order to mark the teeth of the labyrinth sector, they are covered with chalk or the like, the labyrinth sector is lowered gently by aid of the 10 crank 49 so that the teeth just graze the adjacent portions of the guide pins 43, and the barrel 29 is rocked or turned back and forth. The displacement of the chalk or other marking material from the teeth of the labyrinth sector indicates the points or 15 portions to be cut or otherwise shaped. The alterations being made according to the markings thus produced, the part of the combination housed within the lock casing 20 is adapted to coact with the combination part carried by the key, and this key is now the only one which can actuate this particular lock—at least as it now stands.

I do not limit myself to the exact structure shown, or to any precise use to be made 25 of the lock, as variations both in form and action may be made without departing from the spirit of my invention.

The bolt structure disclosed is merely 30 representative, as any bolt of ordinary construction may be employed. While I show only two dolly pins and labyrinth sectors to match, the number may of course be varied as desired. In the device in its 35 entirety suitable changes, within the scope of the mechanical skill of the locksmith and the lockmaker, may be made, the scope of my invention being commensurate with my claims.

40 I claim:—

1. A lock mechanism, comprising a casing, a key to be inserted therein, a ward sector, carried by said key and having a pattern surface of arbitrary form, a labyrinth sector 45 housed within said casing and having an operating surface mating said pattern surface of said key, a rocking barrel housed within said casing and disposed adjacent said labyrinth sector, a bolt controllable by said rocking barrel, and mechanism carried by said rocking barrel and actuated by said ward sector for controlling freedom of movement of said rocking barrel relatively to said labyrinth sector.

55 2. A lock mechanism comprising a casing, a key to be inserted therein, a ward sector carried by said key and having a pattern surface of asymmetrical contour, a labyrinth sector housed within said casing and having 60 a number of teeth staggered in a predetermined path of asymmetrical form dependent upon the contour of said pattern surface of said ward sector, a rocking barrel housed within said casing and disposed adjacent 65 said labyrinth sector, and a bolt operatively

connected with said rocking barrel and controllable thereby.

3. A lock mechanism comprising a casing, a key to be inserted therein, a ward sector carried by said key and having a pattern 70 surface of asymmetrical contour, a labyrinth sector housed within said casing and having a number of teeth staggered in a predetermined path of asymmetrical form dependent upon the contour of said pattern 75 surface of said ward sector, a rocking barrel housed within said casing and disposed concentric to said labyrinth sector and located adjacent the position occupied by said ward sector when said key is inserted 80 in said casing, and a dolly pin carried by said barrel and provided with an end portion for engaging said ward sector, and a guide member carried by said dolly pin for the purpose of controlling freedom of movement of said rocking barrel relatively to 85 said teeth of said labyrinth sector.

4. A combination lock comprising a casing, a key, a ward sector carried by said key and provided with a pattern surface, a labyrinth disposed within said casing and provided with a series of obstructions, a movable member for engaging said ward sector and controllable by the pattern surface thereof, said movable member having a portion 90 extending into said labyrinth and adapted to lodge against some one of said obstructions unless said pattern surface of said ward sector is specially formed to guide said movable member in a clear path of 95 arbitrary direction through said labyrinth, actuating mechanism for shifting said movable member, and a locking member mounted movably in relation to said casing and controllable by shifting movements of said 100 movable member.

5. A device of the character described comprising a key, having a pattern surface, a labyrinth having an obtrusive surface through which a clear path may be traced, a 110 movable member provided with a portion for engaging said pattern surface, said movable member being provided with a portion extending into said labyrinth and adapted to follow the said clear path through said labyrinth if said pattern surface of said key has a predetermined form relatively to the 115 form of said labyrinth, but not otherwise, and a locking member controllable by movements of said movable member.

6. A lock combination comprising a plurality of teeth normally occupying a general fixed position, an actuating member disposed adjacent said teeth and movable relatively thereto, a plurality of dolly pins carried by said actuating member and movable relatively to the same, guiding members carried by said dolly pins for lodging against said teeth except when guided so as to miss them, a key, and ward sectors carried by 120 125 130

said key for moving said dolly pins relatively to said actuating member in order to control said guiding members.

7. A lock combination comprising a plurality of teeth normally occupying a general fixed position, an actuating member disposed adjacent said teeth and movable relatively thereto, a plurality of dolly pins carried by said actuating member and movable relatively to the same, guiding members carried by said dolly pins for lodging against said teeth except when guided so as to miss them, a key, and a plurality of separate ward sectors independent of each other, said ward sectors being interchangeably connected with said key.

8. A lock combination comprising a plurality of teeth normally occupying a general fixed position, an actuating member disposed adjacent said teeth and movable relatively thereto, a plurality of dolly pins carried by said actuating member and movable relatively to the same, guiding members carried by said dolly pins for lodging against said teeth except when guided so as to miss

them, a key, and a plurality of separate members detachably mounted upon said key and severally provided with pattern surfaces for engaging said dolly pins.

9. A lock combination comprising a plurality of teeth normally occupying a general fixed position, an actuating member disposed adjacent said teeth and movable relatively thereto, a plurality of dolly pins carried by said actuating member and movable relatively to the same, guiding members carried by said dolly pins for lodging against said teeth except when guided so as to miss them, a key, and a plurality of ward plates carried by said key and provided severally with pattern surfaces for engaging said dolly pins, said ward plates being staggered relatively to each other.

Signed in the presence of two subscribing witnesses.
